LIGHT SYSTEM FOR KNITTING MACHINES

Filed April 7, 1948

UNITED STATES PATENT OFFICE

2,456,160

LIGHT SYSTEM FOR KNITTING MACHINES

Marco Violandi, Brooklyn, N. Y., assignor to Stop-Motion Devices Corp., Brooklyn, N. Y., a corporation of New York

Application April 7, 1948, Serial No. 19,552

3 Claims.

(Cl. 66—1)

1

This invention relates to new and useful improvements in a light system for knitting machines. It is particularly intended for knitting machines known as closed top machines. In these machines external light cannot reach the interior of the circular material being knitted. A light is therefore necessary within the circular material so that it may be inspected for correcting defects in the knitting operation.

At the present time closed top knitting machines are provided with a light within the circular material being knitted, but the present construction has numerous objectionable features. It is customary to mount a rotary switch upon the top of the vertical shaft of the knitting machine and to connect the usual 110 volt circuit from an outlet on the ceiling to the rotary switch. A cable connects with the rotary switch and is wound around the vertical shaft of the knitting machine and extends downwards and finally extends through an opening in the vertical shaft into its interior and into the interior of the material being knitted. A 110 volt lamp is then mounted in a suitable socket connected with the bottom end of the cable. This construction has numerous disadvantages.

In the first place it is not readily adapted to establishments having extra high ceilings. It requires wiring of the ceiling if the ceiling lacks suitable outlets. Moreover, the use of electric wires hanging down from the ceiling and their connection with a rotary switch, which in turn is connected with a cable extended loosely or firmly around the vertical shaft of the knitting machine presents fire hazards. This is particularly true because of the strong current used, namely, 110 volts or more.

In order to better understand the objects of this invention some consideration must now be given to the circular knitting machine itself. It is customary to provide these machines with a rotary vertical shaft which extends upwards and which supports a yarn carrier for the spools of yarn, guides for the yarn, electric stop motions for the yarn having normally open switches electrically connected in a parallel group, and a coaxially mounted conductor ring associated with a contact arm. The knitting machine is further provided with an electric controller stop means for stopping said knitting machine upon the operation of any one of the stop motion devices, an electric feed circuit connecting said controller stop means, said parallel group of switches, said contact arm, and said conductor ring in series.

2

The dominating object of this invention is to provide the circular knitting machine with a new light system for illuminating the interior of the circular material being knitted, which eliminates the ceiling wiring, the rotary switch at the top of the vertical shaft, and the cable extending down from the rotary switch. In place of these hazardous objects this invention proposes to connect the electric socket which is mounted on the bottom of the rotary vertical shaft of the knitting machine with the electric circuit which controls the stop motions, and the controller mentioned above. An important advantage gained immediately by this substitution would be in a reduction of the fire hazard. The electric feed circuit which connects the controller stop means and the stop motion switches, etc., is of low voltage, for example, 10 or 12 volts. It is supplied by a transformer or by batteries. The use of low voltage reduces fire hazards. It is proposed to use a small wattage lamp in the electric socket in the bottom of said vertical shaft.

Another and important object of this invention is to provide exceptionally simple parts added to the electric circuit of the stop motion switches and controller stop motion means, to provide the necessary connections for lighting the low wattage lamp. Specifically, the only mechanism required is a second conductor ring, a second contact arm engaging the second conductor ring, and a few wires properly connecting the parts in the circuit.

More specifically, the invention proposes to connect the lamp in series with the two conductor rings and to provide a shunt circuit of the feed circuit to the controller stop means and the parallel group of switches, arranged to shunt said controller stop means and said parallel group of switches, and connecting said contact arms, said conductor rings and said lamp in series.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a schematic illustration of a circular knitting machine provided with a lamp system constructed in accordance with this invention.

Fig. 2 is a fragmentary enlarged elevational view of a portion of Fig. 1, with certain parts removed and other parts shown in section.

Fig. 3 is a fragmentary enlarged elevational view of another portion of Fig. 1, with certain parts removed and other parts shown in section.

Fig. 4 is a schematic wiring diagram of the device.

The light system for knitting machines, in accordance with this invention, is used in combination with a circular knitting machine 10 having a vertical rotary shaft 11 extending down into the circular material 12 being knitted by said machine 10 and also extending up and supporting a bobbin table 14 for the spools of yarn 15, various guides 16 for guiding the yarn, electric stop motions 17 of various designs and positioned at various points, as is customary, to protect the yarn, and a coaxially mounted conductor ring 22. The electric stop motions 17 have normally open switches 18 connected in a parallel group 19. These stop motions 17 may be of the types disclosed in patent to Edward Vossen, No. 2,329,427, granted September 14, 1943 for Stop motion devices, and patent to Edward Vossen No. 2,357,713, granted September 5, 1944 for Controller for machines.

The circular knitting machine 10 is also provided with an electric controller stop means 20 for stopping said knitting machine, and an electric feed circuit 21 connecting said controller stop means 20, said parallel group of switches 18, and said contact ring 22 in series. The electric feed circuit 21 comprises the secondary of a transformer 24. The electric controller stop means 20 may be of a design similar to that disclosed in the patent to Vossen, No. 2,357,713, supra. The series circuit may be traced by starting at one end of the secondary coil of the transformer 24, namely, the end indicated by reference numeral 26. From this point a lead 27 connects with the insulated terminal of the controller 20. The circuit then extends through the controller as shown in the Vossen patent, and then connects with the ground 25. The ground 25 connects with the parallel group of switches 18 which in turn are connected with the conductor ring 22. A contact arm 28 engages the conductor ring 22 and connects with the lead 29 which in turn connects with the other end of the secondary coil of the transformer 24. The contact arm 28 is supported on a collar 33 which is mounted on a pipe 30 supported by an insulation collar 31 mounted on the frame 32 of the knitting machine 10.

The new light system, in accordance with this invention, includes a second conductor ring 34 coaxially connected on said vertical shaft 11 and cooperative with a second contact arm 35. This contact arm 35 is supported on an insulation bushing 36 by which it is mounted on the pipe 30 so as to be insulated from the pipe 30. An electric lamp 38 is mounted on the bottom of the vertical shaft 11 within the circular material 12 being knitted by the knitting machine 10 and is for the purpose of lighting the interior of said knitted material 12. Said lamp 38 is connected in a circuit 39 in series with said conductor rings 22 and 34. It is pointed out that a shunt circuit now exists from said feed circuit 21, shunting said controller stop means 20, and said parallel group of switches 18. Said shunt circuit connects said contact arms 28 and 35, said conductor rings 22 and 34, and said lamp 38 in series. This shunt circuit may be traced by starting at the

transformer 24 and tracing the circuit 21 down to the contact arm 35, then continuing to the conductor ring 34, the circuit 39 which includes the lamp 38, the conductor ring 22, the contact arm 28, and the lead 29 back to the transformer 24.

The contact ring 22 is provided with an insulating bushing 40 by which it is mounted on the vertical shaft 11 to be insulated from it. The contact ring 34 is supported on the contact ring 22 by insulation pieces 41. The conductor rings 22 and 34 rotate along with the shaft 11.

The operation of the device may be understood from the following:

When the knitting machine is placed into operation, and the transformer 24 is provided with current, the lamp 38 will burn continuously because it is in a closed circuit which may be traced from the end 26 of the secondary of the transformer 24 to the contact arm 35, the conductor ring 34, the circuit 39, the conductor ring 22, the contact arm 28, and the lead 29 to the other end of the secondary coil of the transformer. This closed circuit which maintains the lamp 38 illuminated at all times does not interfere with the operation of the stop motions 17 and the controller means 20. This may be understood by tracing the stop motion circuit by starting at the point 26 of the secondary of the transformer 24, following the lead 27 to the controller stop means 20, then the ground 25. The circuit then picks up from the ground 25 through the parallel group of stop motion switches 18 to the conductor ring 22, the contact arm 28, and the lead 29 to the other end of the secondary coil of the transformer 24. When any one or more of the switches 18 of the stop motion devices 17 close, an electric circuit will then be established through the ground 25 to the controller 20 which acts to stop the knitting machine 10. In other words, when any one of the stop motions 17 is set into operation by the yarn causing its switch to be closed, the controller 20 is activated to stop the knitting machine 10.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. The combination with a circular knitting machine having a rotary vertical shaft extending down into the circular material being knitted by said machine and extending up and supporting a yarn carrier for the spools of yarn, guides for the yarn, electric stop motions for the yarn with normally open switches electrically connected in a parallel group, and a coaxially mounted conductor ring, a contact arm engaging said conductor ring, and said knitting machine furthermore having an electric controller stop means for stopping said knitting machine and an electric feed circuit connecting said controller stop means, said parallel group of switches, and said contact arm and conductor ring in series, of a second conductor ring coaxially mounted on said vertical shaft, a second contact arm engaging said second conductor ring, a lamp mounted on the bottom portion of said vertical shaft for lighting up the interior of said circular knitted material and connected in series

with said conductor rings, and a shunt circuit from said feed circuit for lighting said lamp and shunting said controller stop means and said parallel group of switches, said shunt circuit connecting said contact arms, said conductor rings and said lamp in series.

2. The combination with a circular knitting machine having a rotary vertical shaft extending down into the circular material being knitted by said machine and extending up and supporting a yarn carrier for the spools of yarn, guides for the yarn, electric stop motions for the yarn with normally open switches electrically connected in a parallel group, and a coaxially mounted conductor ring, a contact arm engaging said conductor ring, and said knitting machine furthermore having an electric controller stop means for stopping said knitting machine, a transformer, and an electric feed circuit connecting said controller stop means, said parallel group of switches, and said contact arm and conductor ring in series with the secondary of said transformer, of a second conductor ring coaxially mounted on said vertical shaft, a second contact arm engaging said second conductor ring, a lamp mounted on the bottom portion

of said vertical shaft for lighting up the interior of said circular knitted material and connected in series with said conductor rings, and a shunt circuit of said feed circuit for lighting said lamp and shunting said controller stop means and said parallel group of switches, and said shunt circuit connecting said contact arms, said conductor rings and said lamp in series with the secondary of said transformer.

3. The combination with a circular knitting machine having a rotary vertical shaft extending down into the circular material being knitted by said machine, of a pair of conductor rings coaxially mounted on said vertical shaft, a contact arm for each of said conductor rings, a lamp mounted on the bottom portion of said vertical shaft for lighting up the interior of said circular knitted material and electrically connected in series with said conductor rings, and an electric feed circuit for lighting said lamp and connecting said contact arms, said conductor rings, and said lamp in series.
